William J. Miller and Armour H. Titus, Jr.,
Galesburg, Ill., and Lawrence H. Wilson, Grosse
Pointe, Mich., assignors to Admiral Corpora-
tion, Chicago, Ill., a corporation of Delaware

Application July 27, 1953, Serial No. 26,153

Term of patent 14 years

(Cl. D81—25)

To all whom it may concern:

Be it known that we, William J. Miller and Armour H. Titus, Jr., citizens of the United States, residing at Galesburg, in the county of Knox, State of Illinois, and Lawrence H. Wilson, a citizen of the United States, residing at Grosse Pointe, in the county of Wayne, in the State of Michigan, have invented a new, original, and ornamental Design for an Instrument Back Panel for a Stove, of which the following is a specification, reference being had to the accompanying drawings, forming a part hereof.

Fig. 1 is a front elevational view of an instrument back panel for a stove, showing our new design;

Fig. 2 is an end view thereof;

Fig. 3 is a sectional view taken on line 3—3 of Fig. 1;

Fig. 4 is a sectional view taken on line 4—4 of Fig. 1;

Fig. 5 is a sectional view taken on line 5—5 of Fig. 1; and

Fig. 6 is a sectional view taken on line 6—6 also of Fig. 1.

The essential features of our design reside in the portions shown in full lines.

We claim:

The ornamental design for an instrument back panel for a stove, as shown and described.

WILLIAM J. MILLER.
ARMOUR H. TITUS, JR.
LAWRENCE H. WILSON.
